(57) **CLAIM**

The ornamental design for a latch for a mechanics pit safety net, as shown.

DESCRIPTION

FIG. 1 is a front perspective view of a latch for a mechanics pit safety net showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a front perspective view thereof showing my new design used with a mechanics pit safety net.

FIG. 9 is a front elevational view thereof.

FIG. 10 is a rear elevational view thereof.

FIG. 11 is a left side elevational view thereof.

FIG. 12 is a right side elevational view thereof.

FIG. 13 is a top plan view thereof.

FIG. 14 is a bottom plan view thereof; and,

FIG. 15 is a front perspective view thereof showing my new design used in a mechanics pit with a safety net.

The broken lines in the drawings illustrate environmental structure and form no part of the claimed design. The dot-dash lines in the drawings illustrate boundary lines and form no part of the claimed design.
